UNITED STATES PATENT OFFICE.

JOHN HOPSON, JR., OF NEW LONDON, CONNECTICUT.

DESIGN FOR A RADIATOR.

SPECIFICATION forming part of Design No. 18,832, dated January 1, 1889.

Application filed August 31, 1888. Serial No. 284,289. Term of patent 7 years.

To all whom it may concern:

Be it known that I, JOHN HOPSON, Jr., of New London, county of New London, and State of Connecticut, have invented and produced a new and original Design for a Radiator, of which the following is a full, clear, and exact description, reference being had to the accompanying drawings, and to the letters of reference marked thereon.

Figure 1 is a view in side elevation of a radiator embodying my new and original design, and Fig. 2 is a view thereof in end elevation.

It should be understood that the radiator may be of any length and any height.

A series of similar sections or parts are represented at A B C D E &c. Each section has a boss or projection, *a a* and *b b*, at top and bottom, showing a free open space between any two sections and between the top and bottom bosses. The bosses are of about the same size, and when united give the appearance of a heavy line at top and bottom, which adds to the general appearance of the radiator. Each section is made up of four uprights, as indicated in the end view, Fig. 2, marked *c d e f*, which join the top and bottom bosses, a slight space being left between these uprights, and each be-

ing shaped after the fashion of a rope made up of heavy strands. The two uprights *c* and *d* are apparently joined at top and bottom by a union-curve, as are also the uprights *e* and *f*, and in end view the two bosses appear to be located between the two pairs of uprights thus joined. The uprights *d* and *e* are a trifle wider than those outside them, or *c* and *f*, as indicated in Fig. 1. The design thus constituted is neat and attractive and quite ornamental.

Having now fully described my design, what I claim as new, and desire to secure by Letters Patent, is—

The herein-described design for a radiator, consisting of a series of similar sections, each having top and bottom bosses, and connecting-uprights with inclined ornamentations in imitation of rope strands, open spaces being left between the uprights and between the lines of top and bottom bosses, as shown.

In testimony that I claim the foregoing I have hereunto set my hand in the presence of two witnesses.

JOHN HOPSON, JR.
